UNITED STATES PATENT OFFICE.

FRANK ANDERSON, OF PEEKSKILL, AND THEODORE M. FOOTE, OF NEW YORK, ASSIGNORS TO THE AMERICAN RAPID TELEGRAPH COMPANY, OF NEW YORK, N. Y.

MECHANISM FOR PERFORATING PAPER FOR TELEGRAPHIC PURPOSES.

SPECIFICATION forming part of Letters Patent No. 228,585, dated June 8, 1880.

Application filed May 3, 1879.

To all whom it may concern:

Be it known that we, FRANK ANDERSON, of Peekskill, in the county of Westchester and State of New York, and THEODORE M. FOOTE, of New York city, New York, have invented certain new and useful Improvements in Mechanism for Perforating Paper for Telegraphic Purposes, of which the following is a specification.

10 This invention relates to certain improvements in that class of telegraphic instruments technically known as "perforators," which are used in connection with the systems of telegraphy described in United States Letters 15 Patent No. 153,064, of July 14, 1874, and No. 172,409, of January 18, 1876, in which the proper "makes and breaks" are made at the transmitting-instrument through the medium of a perforated fillet of paper.

20 The first-mentioned patent relates to a system of transmitting positive and negative currents over a line or conductor by means of perforated paper, whereby, after each recording impulse is sent, an impulse of opposite polarity is transmitted for freeing the line and insuring legibility of the characters at the receiving-instrument.

25 The last-mentioned patent relates to a system of transmission of negative and positive currents over a line or conductor by means of perforated paper, whereby alternate currents of positive and negative electricity are transmitted over a circuit and each impulse made available for recording at the receiving-instrument.

30 The present invention is specially adapted to perforating the paper fillets employed in the above-mentioned systems of telegraphy. It is further designed to provide a means by which 40 the space between the letters, usually left blank, is perforated wholly or in part by a single row of perforations, the object being to record in the space between each two letters, usually left blank, a series of dots in one row, which, in long lines, the recording - current having 45 been transmitted from one pole of the battery, will be lengthened out and invariably recorded as a dash, in any case, however, distinctively marking the space between the letters.

It is essential in these systems that the component perforations forming the integral perforations representing the characters should alternate, and as the characters of the Morse, International, and other character-alphabets employed are composed of an even and uneven number of integral component parts, the 50 perforations would not always alternate properly. Therefore mechanism for effecting this is of vital importance to the transmission of a 55 telegraphic message by alternating currents of positive and negative electricity.

The present invention is especially designed to produce the perforations in the paper employed in the above-mentioned systems.

The special features of the invention consist in the mechanism for operating the punches and selecting the number necessary to form the perforations corresponding to each character to be produced at the receiving-instrument for alternating or reversing the position 65 of the perforations when characters of an uneven number of parts succeed each other in order to prevent two positive or two negative impulses from following each other, which would prevent the proper alternation in the current necessary to produce the characters at the receiving-instrument, and to provide for automatically feeding the paper in proper varying 70 lengths, as more fully hereinafter set forth.

In the drawings, Figure 1 represents a top view of our improved apparatus. Fig. 2 represents a sectional view on the line xx of Fig. 1. Fig. 3 represents a side elevation of the apparatus; Fig. 4, a detached view of the mechanism for operating the bar carrying the 80 punching and paper-feeding mechanism. Fig. 5 represents a detached view of the mechanism for operating the punch-selecting bars. Fig. 6 represents a diagram of a perforated paper for producing the impulses. Fig. 7 represents detached views of the punch-head and punches; and Figs. 8, 9, 10, and 11 diagrams representing the different methods of forming the 85 perforations.

The letter I represents a continuously-revolving shaft driven by any suitable power. Said shaft has rigidly secured to it a ratchet-wheel, j , and has mounted on it a loose sleeve,

J, which carries two cam-disks, H M, adapted to operate the levers or arms G u, as more fully hereinafter explained.

To the disk H is pivoted a pawl or clutch, 5 h, which is adapted to be thrown into and out of gear with the ratchet-wheel j by means of an angle or bell-crank lever, i, pivoted to a suitable standard. The said lever is held in a normal position by means of a short lever, 10 m, pivoted to the standard, and while in said position engages the end of the pawl or clutch h and holds it away from the ratchet-wheel j, permitting the shaft I to revolve independently of the sleeve J and its attachments.

15 The letter P indicates a reciprocating latch-bar, connected, by means of an angle-lever, q, and bar r¹⁰, with an oscillating frame, Q, pivoted in suitable bearings and extending transversely below the key-levers, hereinafter more 20 fully described; so as to be oscillated thereby when one of such levers is depressed, the said frame being held in a normal position by means of a spring. The said bar P is provided near its forward end with an upright projection, p, 25 which sets directly under the lower arm of the angle-lever i, Fig. 4, and forward of said projection is provided with a shoulder, which serves to engage the lower end of the lever m and trip it when the bar r¹⁰ is drawn back by 30 the depression of one of the key-levers, so as to release the angle-lever and permit it to be shifted by means of the spring l, from its normal position. The lower arm of said angle-lever, when in its normal position, engages the 35 lower end of the pawl or clutch h and holds it away from the ratchet j on the shaft; but when it is shifted it releases said pawl, which will be thrown into gear with the ratchet-wheel by means of the spring l, so as to carry the 40 sleeve J with the rotating shaft.

The disk H on the sleeve J is provided at its periphery with a projection, n, which serves to trip the angle-lever i after the sleeve has completed one revolution and return said lever 45 to its normal position, so as to engage the lower end of the clutch or pawl h and release it from the ratchet-wheel.

The bar P is capable of a slight oscillating movement in a vertical position by means of 50 a spring.

When the angle-lever i is thrown out of normal position by the operation of the bar P and lever m, the lower arm, i, of the said angle-lever bears against the projection p on the 55 bar P and holds it down, so as to keep the catch, m⁶ clear of the lower end of the lever m. When the angle-lever is tripped by the projection n on the disk h, the arm i will be elevated, permitting the lever m to spring under 60 its end, and releasing the pressure upon the projection p, allowing the bar P to be elevated, so that the catch m⁶ will engage the lower end of the lever m, so that the lever m will be tripped by said catch m⁶ at the next depression 65 of a key-lever.

The letter G indicates a lever, fulcrumed at

g', its upper end bearing against the cam L on the sleeve J. To said lever is connected one end of a reciprocating bar, F, to the other end of which is attached the punch-head A. Said bar and lever are held in a normal position by means of a spring, k, and are shifted so as to operate the punch-head by the cams L, when a key is depressed and the sleeve J is rotated by the revolving shaft I.

70 The letter E represents the key-levers, which are fulcrumed at e and extend forward to the front of the apparatus, terminating in a series of keys, E'. Said levers are held in a normal position by means of suitable springs.

75 The letter C represents a series of supplementary levers or bars having bearings at one end on a rod, c, the opposite ends being fitted into a sliding rack-bar, D. The said supplementary levers are arranged directly over the key-levers E.

80 To the rear ends of the key-levers are secured transverse pieces f, which serve to raise the supplementary levers or bars C upon the depression of the keys. These pieces f are 85 located successively nearer the ends of the respective levers as they recede from the fulcrums of the punch-selecting bars, as shown in Fig. 1 of the drawings, in order to elevate the said punch-selecting bars the same distance at the depression of each key, as more 95 fully hereinafter specified.

90 The letter B indicates the punch-selecting bars, which extend transversely over the ends of the supplementary levers or bars C, and are pivoted at one end, as indicated at b. The 100 opposite ends of said levers or bars are shaped to correspond with the punches, so that when they are elevated and brought opposite the ends of the said punches they will actuate them 105 in proper order to make the necessary perforations in the slip of paper. The lower edges of these punch-selecting bars are notched or recessed, as indicated in Fig. 5, in such relation to the keys and supplementary bars that 110 when a punch-selecting bar is not required to actuate the proper punch in the formation of a perforation the supplemental lever or bar will be thrown into the notch or recess as it is raised, leaving such punch-selecting bar in 115 a normal position and elevating the other punch-selecting bars to operate in conjunction with the punches to form the perforations for producing the required character.

120 The selection of the punch-selecting bars or levers, however, further depends upon the position given to the supplemental levers, as more fully hereinafter described.

125 The letter X indicates a standard, to which is secured a shaft, X², upon which is journaled a cam-wheel, W, having a compound cam on its periphery or at its edge. Motion is imparted to said wheel by means of a ratchet-wheel, W⁴, and a pawl, P⁴, attached to a swinging arm, x, which in turn is connected to a 130 rod, r. Said rod r is connected to an oscillating frame, R, which is pivoted at S⁴ and

5 S^5 , and which is located transversely under the key-levers E. The depression of certain keys, serves to oscillate said frame, giving a reciprocating movement in a backward direction to the arm x, which carries the pawl P⁴ into the next tooth of the ratchet-wheel W⁴. Upon relieving the key of the pressure and releasing it the frame is returned to its normal position by the spring S⁶, thus throwing the 10 arm and pawl into their normal positions and moving the cam-wheel forward to the extent of one tooth.

The cam-wheel W is prevented from moving backward by the pawl P⁶ acting in and upon 15 the ratchet-wheel W⁴.

The reciprocating rack-bar D carries a pin, w, which is operated by means of the cams on the cam-wheel W and the spring 20 to move said rack-bar back and forth at each depression of the keys and shift the supplemental bars to the right or left a given distance, and change the positions of the respective supplementary bars or levers C, in order to alternate the punch-selecting bars or levers, said supplementary levers, when in position to the right, serving to elevate one series of punch-selecting levers, and when in position to the left to release the first-mentioned bars and elevate others to act in conjunction with the punches. 25 As it is essential for the system herein mentioned that the component perforations forming the integral perforation representing the character shall alternate, it becomes necessary that the polarity interchange shall be effected 30 when the integral perforations consist of an uneven number of component parts. If the integral perforation for a character, as is shown at S, Fig. 9, consists of an even number, then no change occurs for the next letter. If, 35 however, the perforations are unequal, as at I I, Fig. 9, then a change must occur for the next letter, the change being made only when an uneven number of punches are used, and this occurs only on certain characters, as is 40 well known, in which the key-levers of such characters rest on the frame R, so that the depression of the key will swing the frame and actuate the devices, as aforesaid.

The key-levers of such letters that require 45 only an uneven number of punches to make the character are provided with a recess, as shown at 10, Fig. 3, that will permit such levers, when depressed, to pass over the frame R.

A represents a punch-head, carrier, or support for the punches a. Said punch-head is supported in position opposite the punch-selecting bars in any suitable manner, and is so arranged that a reciprocating movement may be given to said punch-head by the rod F, attached to the upright arm G, which is pivoted at g', and has a roller, g, secured to it. Said roller g impinges or rests upon the cam L, and is held firmly thereon by the spring k, as before mentioned. As the cam L is revolved a 50 forward motion is given to the punch-head A by the action of the lever G and rod F, the

spring k serving to return the punch-head to its normal position immediately after the point of the cam farthest from its axis has passed the roller g.

In lieu of the spring k for returning the punch-head to place, a second cam or eccentric may be used, thereby giving a positive and easy to-and-fro motion of the punch-head by the same power and with the least shock 75 to the parts, and with but little noise.

Attached to the punch head or carrier is a metal bar, Z, which passes across and between the punches a a, fitting into the recesses in the same, the bar Z serving to keep the punches a a clear of the bars B when at rest. Attached to the frame or support b is a bar, y, similar to the bar Z, which serves to draw the punches from the die d¹⁰ as the punch-carrier returns to place.

By the use of the pieces y and Z springs that are objectionable for returning the punches are dispensed with and a positive and reliable movement obtained.

While we have shown but six punches—90 three in each row—it is well understood that as many may be used as may be required to form the perforated characters.

The letter Y indicates a series of auxiliary bars, pivoted at b to the support, and parallel with the punch-selecting bars B. The said auxiliary bars are provided with shoulders v near their forward ends, which are formed at varying distances from said ends, for the purpose of regulating the movement of lever V. 95 The arm V is secured by a shouldered screw to a support, T, and the arm t is pivoted to a support, t², and carries a pawl, P¹⁰, which engages and operates a ratchet-wheel, W¹⁰, secured to a drum, S, journaled on a support, d. 100 The said arm V is connected to an arm, t, by means of a link, V', so that the two will move together. The arm V is also secured to a rod, U, which is connected to an oscillating lever, u, fulcrumed at u². The arm u carries a friction-roller, u³, which bears against the cam M on the sleeve J. As the said cam M is rotated the rod U is drawn back from the punches by spring u' until caught by one of the bars Y, which serves as a stop to limit the movement 115 of the arm V and control the distance of its oscillation, and regulate the feed of the paper to correspond to the length of the perforations for each particular character, the said rod being driven forward by the cam M after being arrested by the bars Y, giving a partial rotation to the drum S by the action of the pawl P¹⁰ in connection with the ratchet-wheel W¹⁰. A roller, s, is arranged to bear against the fillet 120 of paper and press it against the periphery of the drum S, so as to draw it through the die, at each movement of said drum and present a fresh portion of the paper to the punches, the movement of the paper, as before stated, depending upon the movement of the arm V, 125 which is regulated by the spacing-bars, which are elevated one at a time, the particular spac-

ing-bar elevated depending upon the length of the integral perforations to produce a given character.

In the several diagrams indicating the perforated strip, the letter a^4 indicates the component parts of the integral perforations representing the characters, which alternate, as clearly shown in Fig. 6, from one line to the other.

10 It will be perceived that where the integral perforations are composed of an even number of component perforations, as indicated by the character representing A, the perforations necessarily alternate; but when a character composed of an uneven number of component perforations follows another of the same kind the component parts of the integral perforations require to be reversed, as indicated by the integral perforations representing the letter S, Fig. 6, in order that the perforations may alternate properly.

In operation the action of the apparatus is as follows: Motion being imparted to the main shaft I by any suitable power, upon depression of a key-lever bearing on the frames Q R the same are depressed, and the following movements take place: The frame Q, upon being depressed, carries forward the connecting-rod r^{10} , which oscillates the bell-crank lever q , giving a backward motion to the catch m^6 of rod P, which trips the oscillating stop-anchor m , which permits the bell-crank lever i to be thrown into position shown in Fig.

4. The arm i , disengaging from the clutch h and resting upon the stop-pin p^5 , serves as a lock to the stop-anchor m , while the point i' rests upon the surface of the flange H of the sleeve L. As the arm i is disengaged from the clutch h the clutch is thrown down upon 40 and into the ratchet-wheel j by the spring l , and revolves therewith one complete revolution at each depression of a key, and is thrown out or disengaged therefrom by the cam n in its revolution coming against the arm i' and throwing the arm i up into the path of the clutch h , where it is held by the stop-anchor m , being thrown by the spring S^{10} against the pin p^5 and under the arm i , so that i acts as a stop to the clutch h . Simulta-

55 neously with the depression of the frame Q the frame R is depressed, moving the rod r attached thereto and the arm X forward, and consequently the pawl p^4 , which is made to take another tooth in the ratchet-wheel W^4 , the wheels W^4 and W being held in place by the stop-pawl p^6 . Simultaneously therewith the lever E of the key, depressed at the point f , raises one of the supplementary bars C, which in turn raises one or more of the punch-selecting bars B and one of the feed-regulating bars Y. It will be perceived, then, that the depression of the frames Q R, the action of the devices r^{10} q P p M i i' h and devices r v p^4 , and the raising of the bars C B Y all occur in the same instant or period of time.

Immediately upon the clutch taking into the revolving ratchet or spur wheel j the said clutch and the cams on the sleeve J become a part of the shaft I, and revolve therewith, and the following movements take place: The cam L acts upon the roller g on the lever G, moving, by means of the connecting-rod F, the punch-carrier forward and the punches up to and against the punch-selecting bars that have been raised, thereby driving the punches into the die d^{10} and perforating the paper, the spring k serving to throw the punch-carrier back to place immediately as that part of the cam farthest from the axis has passed in its revolution the roller g . Simultaneously with the movement of the cam L the cam M changes its position and permits the spring u' to contract and move the rod u and the arm V back from the paper until the arm V is stopped by the raised-paper feed-spacing bar Y. The cam L and cam M are so arranged in relation to each other that immediately after the cam L has carried the punch-head forward and perforated the paper, and permitted the return or partial return of the punch-carrier and the withdrawal of the punches from the paper, the cam M, in its revolution, drives the rod U, arm V and t forward, partially revolving the roller S by the action of the pawl p^{10} on the ratchet-wheel W^{10} , the movement of the paper depending upon the backward movement of the arm V, which is regulated by the bars Y, as hereinbefore explained.

It will be observed that the above-described operations take place upon the depression of the key.

The operations and movements that occur when the key is released are as follows: The frame Q is returned to place by the spring S^5 , thereby carrying the catch m^6 by a forward lateral motion into normal position, as shown in Fig. 2. Simultaneously therewith the frame R is returned to place by the spring s^6 , Fig. 3, which carries forward the rod r , arm X, and pawl p^4 , Fig. 5, driving the compound cam-wheel W by means of the ratchet-wheel W^4 , the wheel W, in turn, in its movement acting on the pin w in the rack-bar D, and held against W by the spring u' , carries the rack-bar D and supplementary bars C to the right or left, thereby changing the position of the bars C in relation to the levers E and bars B. Should now the same key be again depressed the same movements would occur and the same results be obtained, excepting only that, the position of the bars C having been changed in relation to the bars B and levers E, different punch-selecting bars B would be raised and different punches used; and if, for instance, the character punched had been as shown in Fig. 10, upon repeating of the same they would appear as shown in Fig. 11, the first component part of the integral perforation representing the character being in one case in the top line of row of perforations, and in the other case in

the bottom row, the same being caused by using the first top punch first in one case and the first bottom punch first in the other case.

It will be observed that the above explana-

5 tion is only in reference to such keys that bear upon the frame R. It applies, however, to all the keys, with this exception, that such keys that are provided with the recess 10, Fig. 3, pass over the frame R, when they are de-
10 pressed and do not operate the same, so that the mechanism connected with R is not oper-
ated, and the position of the bars C remain unchanged unless a key is depressed that bears on the frame R.

15 We do not limit ourselves to the method shown of changing the position of the bars C, as there are many other methods of effecting the same. Neither do we confine ourselves to the precise method of controlling the clutch h,
20 as various other devices may be used without departing from the general principle.

What we claim is—

1. In a telegraphic perforator, the combination of a reciprocating punch-head carrying a series of movable punches and a die with a series of separately and independently adjustable punch-selectors, adapted to be brought into the paths of the said punches and hold them while the die is forced against them,
30 and mechanism for operating said punch-head and punch-selectors, respectively, substantially as described.

2. In a telegraphic perforator, the combination of the key-levers, the supplementary levers actuated by said key-levers, devices for giving said supplementary levers a lateral motion, the notched punch-selecting bars, and the reciprocating punch-head carrying the series of movable punches and die, substan-
40 tially as described.

3. In combination with the key-levers, a series of punch-selecting bars and mechanism for alternating the same to select the punches in the punch head or carrier, substantially as specified.

45 4. In combination with the series of separately movable key-levers, movable punch-selectors, and punch-head carrying a series of punches, mechanism for operating the punch-head and punch-selectors at each depression of a key, substantially as described.

5. The combination, with a series of key-levers, a series of punch-selectors operated by said levers, and a reciprocating punch-head carrying a series of movable punches, of a rotating shaft carrying a loosely-mounted sleeve adapted to operate the punch-head through intermediate connections, and mechanism for locking the sleeve to the shaft simultaneously with the depression of each key-lever, substantially as described.

6. The combination, with the key-levers, punch-selecting bars, and punches, of the paper-feeding devices and the auxiliary bars Y, adapted for operation by the key-levers to

regulate the feed to correspond with the punch-selecting bars operated at the same time, substantially as described.

7. In combination with the key-levers and the supplementary levers, mechanism for operating a punch-head, and a drum for moving the paper, and its operating mechanism, so arranged in relation to each other that the punches will be operated in advance of the paper-feed devices, substantially as specified. 70

8. In combination with the rotating shaft and loosely-fitting sleeve, carrying the cams for operating the punch and feed devices, the ratchet on said shaft, and pawl on the sleeve and the angle-lever, and mechanism for tripping the same, substantially as specified. 75

9. In combination with the angle-lever for tripping the pawl on the sleeve of the rotating shaft, the lever m and its spring, the bar P and its spring, and the projection on said bar, 80 for controlling the movement of the bar P, to engage the lever m and hold it and the angle-lever in normal position, substantially as specified.

10. In combination with the key-levers and supplementary levers, the oscillating frame R, rod , arm x, and pawl and ratchet, by means of which the cam W is rotated to impart a reciprocating motion to the rack-bar and alternate the lifting of the punch-selecting bars, 85 substantially as specified.

11. In combination with the paper-drum and its rotating devices, the arm V, connected to said rotating devices, the rotary shaft A, and devices communicating positive motion 100 in one direction therefrom to said arm, a spring for actuating said arm, and the bars Y, having shoulders or stops y at different distances from their free ends, and the key-levers for operating said bars, substantially 105 as described.

12. The combination, with the reciprocating punch-head carrying a die and having the punches mounted loosely therein, of the bar Z, attached to said punch-head and extending through recesses in said punches, for limiting the movement of the same, and a stationary stop-bar adapted to retain said punches in a given position while the die is withdrawn therefrom, substantially as de- 110 scribed. 115

13. In combination with the key-levers and supplementary levers, the transverse pieces, arranged successively nearer the ends of the levers as they recede from the fulcrum of the 120 punch-selecting bars, for the purpose of elevating them equally, substantially as specified.

14. In a telegraphic perforator, the combination of a series of movable punches arranged in two rows, a series of punch-selecting bars, a series of key-levers, some of which are adapted to operate bars for selecting punches to form an even number of characters and others to operate bars for selecting punches 125 130

- to form an uneven number of characters, and mechanism for causing the bar - selecting punches to form uneven numbers of characters to alternately assume reversed positions 5 with respect to the rows of punches as said bars are successively operated, thereby causing alternately-reversed positions of the perforations composing uneven groups of characters in the paper, substantially as set forth.
- 10 15. A telegraphic perforated transmitting fillet in which the perforations are in two rows, and the integral perforations representing the characters are alternately in opposite rows,

having an extra perforation or a series of extra perforations between each two letters, serving to define and separate the letters, substantially as described. 15

In testimony that we claim the foregoing we have hereunto set our hands in the presence of the subscribing witnesses.
